WATER DAM FOR GRAVES

Albert L. Malott and Charles E. Robertson,
Springfield, Ohio

Application October 9, 1937, Serial No. 168,230

3 Claims. (Cl. 27—29)

This invention relates to a water dam for freshly dug graves, it more particularly relating to a moisture-proof dam which may be inserted in the grave prior to the lowering of the burial casket therein which will hold back any water which may be in the bottom of the grave so that such water will not be exposed to view but will impart to the bottom of the grave a dry appearance prior to the burial.

10 One of the objects of the invention is to provide a water-proof dam of simple and cheap construction which may be inserted in the grave prior to the burial and which will enclose either a wooden box or a burial vault in which the burial 15 casket is placed, this water-proof dam being of a size to fit the grave and to receive the wooden box or vault.

A further and more specific object of the invention is to provide a dam of the character referred to which may be constructed in the form 20 of a flexible bag of cheap water-proof material, such as paper which has been treated to make it water-proof, and which may be readily folded in compact form for shipping and storage prior to 25 the time that it is to be used in the grave.

A further object of the invention is to provide a rigid form for a flexible foldable dam of the character described which will hold the dam in open position in the grave whereby a vault or 30 other burial casket receptacle may be placed therein.

A further and more specific object is to provide a rigid form of the character referred to which may be readily adjustable to different sizes to 35 accommodate it to different sized water-proof bags to suit the size of the grave.

In the accompanying drawings:

Fig. 1 is a perspective view of a foldable water-proof bag employed in connection with this invention, the bag being shown in open position.

Fig. 2 is a side elevation of the bag in partly folded position, one of the sides only being shown open.

Fig. 3 is a plan view of the blank of which the bag is formed.

Fig. 4 is a perspective view of the rigid form used to hold the bag in open position in the grave.

Fig. 5 is a view partly in elevation and partly in perspective of one of the sides and one of the ends of the form.

Fig. 6 is a view partly in elevation and partly in perspective of another one of the sides and an end of the form; the side in this figure being one 55 that mates with the side shown in Fig. 5.

Fig. 7 is an elevation of one of the end members of the form before it has been bent to shape.

Fig. 8 is a view in perspective of upper portions of two of the side members of the form shown in assembled relation, one of the members being shown in section.

Fig. 8a is a view in perspective of lower portions of two of the side members of the form shown in assembled relation, one of the members being shown in section.

Fig. 9 is a vertical section of upper portions of two of the side members at the point where they are slidably connected together.

Fig. 9a is a vertical section of lower portions of two of the side members at points where they are connected together.

Fig. 10 is a view of another end member of the form before it has been bent to shape, this member being a mating one to that shown in Fig. 7.

Fig. 11 is an elevation of one of the side members of the form before it has been bent to shape.

Fig. 12 is an elevation of one of the side members of the form before it has been bent to shape, this member being a mating one to that shown in Fig. 11.

Fig. 13 is a vertical section taken through a grave near the end thereof showing the moisture-proof container and its form also in vertical section; this view showing in end elevation a metallic vault of a well-known construction.

Fig. 14 is also a vertical section taken through a grave near the end thereof, showing the moisture-proof container placed directly upon a wooden box which receives the casket, the box being shown in vertical section, and a casket 35 shown therein in end elevation.

Referring first to Figs. 1, 2 and 3 of the drawings, there is shown a preferred form of moisture-proof dam, this dam being preferably made in the form of a flexible bag of paper which has 40 been suitably water-proofed, although it may be formed of any other suitable material such as water-proof sheet rubber. This bag has a bottom 1, sides 2 and ends 3, the sides and ends being connected by wings 4, a pair of wings being 45 provided at each corner of the blank with a score line 5 therebetween. Where the wings connect with the sides and ends additional score lines 6 are provided and where the sides and ends connect with the bottom 1 there are score lines 7. 50 Each of the sides 2 also has score lines 8. By this arrangement the flexible bag can be folded upon itself for shipment and storage and readily opened out for use. When collapsed the ends 3 are folded upon the bottom 1 and the wings 4 55

folded upon the outside of the respective ends, each of the sides being folded upon itself along the score line 8. When the bag is unfolded to the open position shown in Fig. 1, each of the 5 ends 3 and wings 4 of each pair of wings will be connected together in any suitable way such as by staples 9.

The form which is employed to hold the flexible bag in open position in the grave is illustrated 10 in Figs. 4 to 12, inclusive. This form is preferably constructed of sheet metal and is preferably made adjustable to adapt it to different sized graves. The form is open at the top and bottom and in the preferred construction the form has 15 two sides and two ends. Each of the sides is in two sections 10 and 11 and each of the ends is also in two sections 12 and 13. Each of the side sections 10 is bent along the dotted lines 14, 15 and 15' (Fig. 11), to form a laterally-extending 20 channel 16 and has its lower edge bent upon the lines 17, 18 and 19 to form a laterally-extending channel 20 preferably of larger dimensions than the channel 16. Each of the side members 11 has its upper edge bent upon the dotted line 21 to 25 form a lateral flange 22 and has its lower edge bent upon the dotted line 23 to form a lateral flange 24, (Fig. 12), the flange 24 being of greater width than the flange 22.

Each of the end members 12 has its upper 30 edges similarly bent upon the dotted lines 25, 26 and 27 and its lower edge bent upon the lines 28, 29 and 30 (Fig. 7) to form laterally-extending channels 31 and 32, and each of the end members 13 has its upper and lower edges bent on 35 the lines 33 and 34 (Fig. 10) to form flanges 35 and 36. The flanges 22 and 24 of the side sections 11 are slidably mounted in the channels 16 and 20 of the side sections 10 so that the length of the form may be suitably adjusted and the 40 flanges 35 and 36 of the end sections 13 are slidably mounted in the channels 31 and 32 of the mating end members 12 so that the width of the form may be adjusted.

The side members 10 and 11 and the end members 12 and 13 are hinged together by ordinary 45 strap hinges 37 to hold the parts in the open position shown in Fig. 4 but permit the form to be folded for transportation or storage.

In operation, when the devices are to be used 50 in a grave G which is to receive a grave vault V such as shown in Fig. 13, the metallic form is used to hold the flexible water-proof bag in position in the grave. In this case the metallic

form is inserted in the bag before the form and bag are placed in the grave and after the casket has been lowered in the grave and the upper portion of the vault lowered and locked to position on the base the metallic form is withdrawn for 5 further use, leaving the water-proof bag in the grave. If, however, a metallic or other form of vault is not used to receive the casket but merely a wooden box such as shown at B in Fig. 14 10 to receive the casket C, then the metallic form 14 may be dispensed with, if desired, and the water-proof bag placed upon the box before the box is placed in the grave.

Referring to Fig. 13, the bag and its form is 15 each made of a depth sufficient to insure the damming of any water which may be in the grave, the bag being preferably somewhat deeper than the form so as to permit the upper edges 2' of the side to be bent over the upper edges of the sides of the form to keep the sides of the bag from sagging. As shown in Fig. 14 the upper edges 2' of the sides of the bag are also bent over the box B for the same purpose.

Having thus described our invention, we claim:

1. In a device of the character described, a 25 member formed of water-proof material closed at its bottom, sides and ends adapted to be fitted in a grave and having an open top to receive the casket, said member being of a collapsible character, and means insertable therein to hold 30 the member in open position.

2. In a device of the character described, a member formed of water-proof material closed at its bottom, sides and ends adapted to be fitted in a grave and having an open top to receive 35 the casket, said member being formed of flexible water-proof material adapted to be folded for transportation and storage, and a rigid form upon which said member is placed to hold said member in open position in the grave, said rigid form 40 being open at the top and bottom to permit removal thereof from the grave after the casket has been deposited.

3. In a device of the character described, a member formed of flexible water-proof material 45 having a bottom, sides and ends but open at the top, said member being fitted in a grave to act as a dam against the entrance of water in that portion of the grave which receives the casket, and a rigid form to receive said member to hold 50 it in open position in the grave.

ALBERT L. MALOTT.

CHARLES E. ROBERTSON.
